UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

DIFFERENTIAL-MICROPHONE REPEATER.

1,089,534.

Specification of Letters Patent. Patented Mar. 10, 1914.

Application filed February 27, 1911. Serial No. 611,111.

To all whom it may concern:

Be it known that I, JOHN J. COMER, a citizen of the United States of America, and resident of Chicago, Cook county, Illinois, **5** have invented a certain new and useful Improvement in Differential-Microphone Repeaters, of which the following is a specification.

My invention relates to microphone transmitters in general, but more particularly to microphones of the so-called differential type, and especially to differential microphone repeaters for use in loud speaking or other telephone systems.

15 Generally stated, the object of my invention is to provide a novel form of differential microphone for use in telephone transmitters, or for use in telephone repeaters, in which the arrangement of the electrodes is **20** simple and effective, and in which the operative connection or stem does not, in order to connect with a springy or resilient member, when the microphone is used in a repeater, pass through both walls thereof, but **25** only through one, whereby the construction and mode of operation are simplified, and whereby the method of regulating the air gap provided between a flexible diaphragm and a magnet, which diaphragm serves as **30** the armature and is the said springy or resilient member connected with said stem, is rendered more satisfactory than heretofore, as will hereinafter more fully appear.

To the foregoing and other useful ends, **35** my invention consists in matters hereinafter set forth and claimed.

In the accompanying drawings Figure 1 is a view on one side of a differential microphone repeater with the casing thereof **40** removed to show the construction. Fig. 2 is a similar view of another side of said repeater. Fig. 3 is a view similar to Fig. 2, showing some of the parts separated. Fig. 4 is an enlarged longitudinal section of the **45** forward end portion of the repeater shown in preceding figures, the rear end thereof being shown broken away for convenience of illustration. Fig. 5 is a front elevation of the said repeater, on the same scale as Figs. **50** 1, 2 and 3. Fig. 6 is an end view, on the same scale as Fig. 5, of the magnet structure with the cap or microphone removed. Fig. 7 is a view of the inside of the said cap as **55** it appears when removed from the structure of the repeater.

As thus illustrated, the permanent magnet A has the pole pieces *a*, which are arranged to engage the opposing surfaces of the limbs *a'*, being separated and held in place by the block *a²* that encircles the bolt **60** *a²*. The said limbs are provided with brackets *a⁴* secured thereto, and the said bolt extends through the said bracket and the limbs of the magnet, and through the said pole pieces and the said block, whereby the magnet structure is clamped tightly together. A block of insulation *a⁵* is secured to the top of said bolt by a small screw *a⁶*, and this block of insulation carries the two binding posts *a⁷* and *a⁸*, whereby suitable circuit connections can be made. The pole pieces *a* have windings *a⁹*, and these electromagnets are partially inclosed by a cup *a¹⁰*, the back of which is secured to the bracket *a⁴*, the back of said cup being apertured to receive **70** the said polarized electromagnets. A cap *a¹¹* closes the open front of the said cup, being screwed thereon, thus forming a front wall for the box or chamber in which the electromagnets are partially inclosed. A **75** ring of insulation bears against the wall of said cap, and a metal ring *a¹²* is superimposed thereon, whereby a shoulder is formed for the marginal portions of the diaphragm *a¹²*, which latter is of any suitable material, **80** preferably metal of a paramagnetic character. The said diaphragm is held in place by a ring of insulation *a¹⁴*, which bears against the other side thereof, and near the margin, and by a metal ring *a¹⁵* that screws into the **85** threaded interior of the cap, which ring is provided with notches *a¹⁶* by which it can be screwed into place to clamp the diaphragm tightly in position. The metal ring *a¹³* may be used as a terminal ring for making electrical connection. So far, it will be seen that the structure resembles an ordinary receiver, as the diaphragm *a¹²* will be **90** vibrated by the telephone currents passing through the coils of the magnet. **95**

The microphone box B consists of a pair of rings *b* that are spaced apart by washers *b'*, and which are clamped in place by bolts or studs *b²* having their heads fastened to the front wall of the cap *a¹¹*, said bolts or **100** studs having sleeves of insulation *b³* that extend from the outer surface of said cap to the inner surface of the metal plate *b⁴*, in the manner shown. A stationary electrode *b⁵* engages the outer surface of one ring *b*, and **105**

a similar electrode b^6 engages the outer surface of the other ring b , whereby the opening through said rings is closed at front and back to form a chamber for the granular carbon b^7 , and for the movable or plunger-like electrode b^8 which divides the said carbon into two separate masses or bodies. These electrodes can be of carbon, or any other suitable material. The said stationary electrodes are backed by metal terminal plates b^9 and b^{10} , and these plates are insulated from the cap and the outer plate b^4 respectively, by plates of insulation b^{11} and b^{12} , in the manner shown. Thus, the superimposed layers of metal, carbon and insulation are all clamped tightly in place and upon each other to form a box or hollow structure. The electrode b^8 is connected by a stem b^{13} with the diaphragm a^{12} , said electrode being secured to the said stem by nuts which engage the threaded portion of the stem, whereby the electrode can be adjusted properly on the stem. The space between the opposing surfaces of the rings b is filled with soft fibrous material b^{14} , such as fluffy asbestos or other similar material, which engages the outer edges of the electrode b^8 , and which prevents the granular carbon from escaping at the circumference of the microphone box.

Thus it will be seen that I provide an improved differential microphone repeater in which the stem of the flexible electrode extends through only one side of the box, and in which the latter is of simple and efficient construction, and of such character that heavy currents can be carried without danger of overheating or other trouble. The air gap between the diaphragm a^{12} and the pole pieces can be accurately regulated by the adjustment of the screw threaded cap a^{11} , which is then locked in place by a threaded ring or lock nut a^{17} , it being understood that the first or approximate adjustment of these different parts is obtained by properly adjusting the electrode b^8 on the stem b^{13} at the time that the same is secured thereon by the said nuts or other suitable devices. The said microphone box can be easily taken apart for the purpose of repair or substitution. It can be filled with the granular carbon before the front and back plates or disk-like electrodes are secured in place. The insulating parts of the microphone box can be of any suitable character, such as mica or fiber or rubber vulcanite, or any other suitable insulating material that can stand considerable heat if

it becomes necessary to employ heavy currents.

With the construction shown, it will be observed that the granular carbon at one side of the movable electrode is separated from the granular carbon at the other side thereof. This does not interfere with the free and proper vibration of the said electrode, and the results, I find, with this construction, are entirely satisfactory. It will be seen that a similar packing of fibrous material b^{15} is placed around the stem in the perforation of the back electrode, whereby the granular carbon is prevented from escaping at this point.

When the cap a^{11} is removed, it carries with it the entire microphone device, and also carries with it the diaphragm by which the microphone is operated, thus facilitating adjustment of these parts for accurate operation thereof. Also, the adjustment of the air gap between the diaphragm and the magnet is accomplished by adjusting both the diaphragm and the microphone. In other words, the microphone and diaphragm are moved toward and away from the magnet to regulate the air gap.

What I claim as my invention is:

1. In a microphone repeater, a microphone box provided with a movable stem for the operation thereof, a magnet, a diaphragm disposed in position to be directly acted upon and vibrated by said magnet, said diaphragm being connected with the said stem, a cup partially inclosing said magnet, and a removable cap screwed upon the said cup, which cap carries with it when removed both the said diaphragm and said microphone box, said diaphragm being mounted on one side of said cap and the microphone box on the other side thereof.

2. In a microphone repeater, a magnet, a cup partially inclosing said magnet, a cap for said cup removably secured thereto, a diaphragm mounted adjacent the poles of said magnet and carried by said cap, a microphone transmitter mounted on the outside of said cap, and a connection between said diaphragm and said transmitter passing through said cap.

Signed by me at Chicago, Illinois, this 18th day of Feb. 1911.

JOHN J. COMER.
